UNITED STATES PATENT OFFICE.

SAMUEL B. SADLER, JAMES R. SADLER, AND DAVID M. CARTER, OF FAIRFIELD, NORTH CAROLINA.

CAR-COUPING.

SPECIFICATION forming part of Letters Patent No. 438,024, dated October 7, 1890.

Application filed July 2, 1890. Serial No. 357,582. (No model.)

To all whom it may concern:

Be it known that we, SAMUEL B. SADLER, JAMES R. SADLER, and DAVID M. CARTER, residing at Fairfield, Hyde county, and State 5 of North Carolina, have invented a new and Improved Car-Coupling, of which the following is a specification.

This invention is an improved automatic car-coupling; and it consists in certain features of construction and novel combinations of parts, as will be hereinafter described, and pointed out in the claims.

In the drawings, Figure 1 is a perspective view of one end of a car provided with my 15 improvements. Fig. 2 is a top plan view of the draw-head, parts being broken away and others shown in section. Fig. 3 is a vertical section of one end of the car and of parts of the improved coupler. Fig. 4 is a vertical 20 section on about line 4-4 of Fig. 2, and Figs. 5, 6, and 7 are detail views.

The draw-head A may be secured to the car B in any suitable manner, and is formed with the open mouth a, preferably flared in the 25 usual manner, as shown. In this draw-head we secure the coupling bar or section C, which is preferably secured to the draw-head by a vertical pivot D near the rear end of the coupling-bar, the said bar being narrower 30 than the interior of the draw-head, so such bar may swing laterally at its forward end. Springs E E are arranged to bear between the opposite sides of the coupling-bar and the adjacent walls of the draw-head, so that the 35 coupling-bar will be held normally in its desired straight position.

The coupling-bar is shown as formed with arms F, f, and G, extended forward from the body of the coupling-bar and projecting beyond the front end of the draw-head. The arm F is arranged above the arm f, with an intervening space between said arms, while the arm G is arranged to one side of arms F and f and in a horizontal plane with the space 45 between arms F and f, the free ends of arms F and f being flared on their inner faces, and the free end of the arm G being pointed, as shown, so that the end or point of arm G of one coupling will be guided between the ends 50 of the arms F f of the meeting coupling. It will be noticed that the arm G is set suffi-

ciently to one side of arms F f to provide an intervening space in which hangs the trigger presently described. The arms F f have co-incident holes H h, and the arm G has a hole 55 I, such holes H h I being to receive the coupling-pins in the coupled position of the parts. A hole J is formed in the top of the draw-head in register with openings H h, through which hole the coupling-pin plays freely. 60 This coupling-pin K is guided by a guide-bracket L, secured to the car and extended forward over the draw-head, the downward movement of the said pin being limited by the shoulder k thereon engaging upon the 65 draw-head, and its upward movement being limited by cross-pin M, which bears below the guide-bracket L, and is threaded at its center to the coupling-pin so it can be withdrawn to permit the removal of the pin for any de- 70 sired purpose. At its upper end the pin K is provided with an arm N, forming a bearing for engagement by the lifting-arm of the rocking shaft O. This shaft O is journaled to the end of the car, has at its ends crank-handles o, by which it may be turned, and is provided at about its middle with the lifting-arm P, having at its end a pin p to engage 75 under the arm N of the coupling-pin.

In guides Q on the end of the car we support the vertical slide-bar R, which is connected at its lower end to the lifting-arm P and extends at its upper end in convenient reach from the top of the car. Thus the pin can be withdrawn from the top of the car by 85 means of the vertical slide-bar and from the sides of the car by means of the rock-shaft, before described.

To hold the pin elevated in position to couple a meeting draw-head, we provide a 90 latch-plate S, supported by the draw-head and actuated by a spring T, so it will normally press against the coupling-pin and will enter a notch U therein when the pin is raised and hold the pin so elevated until the latch-plate 95 is released. To release this plate, we provide it with a projection s, which extends down into position for engagement by a trigger V, which is a lever pivoted at v and arranged at its upper end to engage projection s to operate the slide-latch, and having its lower arm arranged to be engaged by a pin or projec- 100

tion W at the end of arm G of the meeting draw-head. In the construction shown the slide-latch S is approximately L-shaped, and is supported in a similarly-shaped recess X in the top of the draw-head, and covered by a plate x, as shown. At its front end the plate S has a lateral wing which supports the projecting portion s, and the main portion of the latch has an opening Y, which registers with opening T in the draw-head. The wall of opening Y forms the portion which engages the pin by entering the notch U in said pin.

In operation it will be seen that if the coupling-pins of one or both of the meeting draw-heads are elevated and the said draw-heads are brought together, the arms G of each coupling will enter between the arms F f of the other. The pin on said arms G will strike the triggers and release the pins K, which will fall through the openings in arms F, G, and f, and hold the cars coupled, the coupling being automatically effected. The cars may be uncoupled from either side or the top 25 of the car, as before described.

Having thus described our invention, what we claim, and desire to secure by Letters Patent, is—

1. In the herein-described coupling, the combination of the draw-head, the coupling-pin, the latch for holding said pin elevated, such latch being movable forward to release the pin, and the trigger by which to move the latch forward to release the pin, such trigger being arranged for operation by the coupling devices of the meeting car, all substantially as and for the purposes set forth.

2. In the herein-described coupling, the combination of the coupling-pin, the draw-head having an opening or hole for the coupling-pin, the latch having an opening or hole within which the coupling-pin is held in both its coupled and uncoupled positions, a spring for actuating said latch, and means whereby 45 the latch may be operated in opposition to said actuating-spring, substantially as set forth.

3. In the herein-described coupling, the combination of the draw-head, the latch arranged to hold the coupling-pin elevated and provided with a downward projection, the spring for actuating said latch, and the trigger pivoted to the draw-head and having its upper end arranged to engage the projection of the 55 latch and its lower end arranged to be engaged by the coupling devices of the meeting draw-head, substantially as set forth.

4. In a car-coupling, a coupling-bar formed with arms F, f, and G, substantially as set forth.

5. The improved draw-bar for car-couplings, substantially as herein described, consisting of the arms F f, arranged one above the other and separated and having coincident openings for the coupling-pin, and the arm G, arranged alongside of the arms F f and in a common plane with the space between said arms F f, all substantially as and for the purposes set forth.

6. The combination, substantially as described, of the draw-head, the coupling-bar pivoted at its rear end in said draw-head and provided with arms F, f, and G, and the springs bearing between the opposite sides of the coupling-bar and the draw-head, all substantially as described, and for the purposes set forth.

7. In the herein-described coupling, the combination of the draw-head, the coupling-pin having at its upper end an arm for engagement by the lifting-arm, the rock-shaft having a lifting-arm for engagement with the arm of the coupling-pin, and the vertical slide-bar connected at its lower end with the arm of the coupling-pin, all substantially as and for the purposes set forth.

8. In a car-coupling, the combination of the draw-head provided with an opening for the coupling-pin and with a recess for the latch-plate, the latch-plate fitted in the recess of the draw-head and having an opening to embrace the coupling-pin and with a downwardly-projecting portion, the spring for actuating said latch-plate, the coupling-bar arranged in the draw-head and having arms F, f, and G, with an intervening space between the bars F, f, and G, and the trigger pivoted to the draw-head and arranged at its upper end to engage the downward projection of the latch-plate and projecting at its lower end between the arm G and the arms F f of the coupling-bar, substantially as set forth.

9. The combination of the draw-head, the guide-bracket extended thereover and having an opening for the coupling-pin, the coupling-pin having a notch U and provided at its upper end with an arm, the stop-pin connected with the coupling-pin below the guide-bracket, the latch-plate arranged to engage in the notch U of the coupling-pin, the spring for actuating the latch, the trigger for moving the said latch in opposition to its spring, and the coupling-bar, all substantially as described, and for the purposes set forth.
